(57) **CLAIM**

The ornamental design for a bendable straw, as shown and described.

DESCRIPTION

FIG. 1 is a top perspective view of a bendable straw.

FIG. 2 is a bottom perspective view thereof.

FIG. 3 is a front view thereof (rear view is mirror).

FIG. 4 is left-side view of a bendable straw (right side view is mirror).

FIG. 5 is a top view thereof (bottom view is mirror).

FIG. 6 is a top perspective view of the bendable straw inserted into a beverage container with a food container attached to the beverage container.

FIG. 7 is a bottom perspective view of the bendable straw inserted into a beverage container with a food container attached to the beverage container.

FIG. 8 is a top perspective view of the bendable straw detached from a beverage container and a food container; and,

FIG. 9 is a bottom perspective view of the bendable straw detached from a beverage container and a food container. The broken lines show a beverage container and a food container that are environment only and form no part of the claimed design.

1 Claim, 3 Drawing Sheets
